[57] CLAIM

The ornamental design for a combined electric ceiling fan and light, as shown and described.

DESCRIPTION

FIG. 1 is a bottom perspective view of a combined ceiling fan and light showing my new design; FIG. 2 is an enlarged side elevation view thereof, the other side views being substantially identical to that shown;

FIG. 3 is an enlarged bottom plan view thereof; and, FIG. 4 is an enlarged top plan view thereof.

The broken line showing of environmental structure in FIGS. 1, 2 and 4, is for illustrative purposes only and forms no part of the claimed design.

The blades have been broken away in FIGS. 2-4 for convenience of illustration.

FIG. 1

FIG. 2

FIG. 4
